SUPERHETERODYNE RECEIVER

John Forrest Ramsay, Chelmsford, and Arthur Leonard Oliver, Wimbledon Park, London, England, assignors to Radio Corporation of America, a corporation of Delaware

Application March 1, 1939, Serial No. 259,126
In Great Britain March 4, 1938

6 Claims. (Cl. 250—20)

This invention relates to superheterodyne receivers.

Practical considerations in superheterodyne receiver design have resulted in the adoption of intermediate frequencies (I. F.) of more or less conventional fairly low values, two typical practical values being 110 and 450 k. c. per second. There are also well known advantages in adopting as the variable tunable oscillator of a superheterodyne receiver an oscillator of relatively high frequency, e. g. one covering a range of about 2½ to 4 megacycles.

It is known to satisfy these requirements by providing two different local oscillators and two different I. F. amplifiers in a superheterodyne receiver, the first local oscillator changing the receiver wave frequency to the first I. F. and the second local oscillator changing the first I. F. to the second I. F. This proposal, however, necessarily involves considerable increase in the complexity and cost of the receiver and moreover offers some disadvantages in the case of a receiver fitted with automatic frequency control (A. F. C.) for if, as has hitherto been proposed, the A. F. C. system operates to control the frequency of the second oscillator only, although the first I. F. is thus automatically "centred" at the mid-band frequency of the second I. F. amplifier, unless the two local oscillators are very accurately aligned the received frequency will be in effect displaced from the central frequency of the first I. F. amplifier.

The main object of the present invention in its broadest aspect is to provide a superheterodyne receiver wherein the requirements of using an I. F. of conventional low value and at the same time employing a variable tunable local oscillator of high frequency may be satisfied in a simple manner.

An important subordinate object of the invention is to provide a superheterodyne receiver wherein an A. F. C. system operates to control the frequency of an oscillator which does not have to be manually varied in tuning but does not present the disadvantage of possible "misalignment" as above described. It will be appreciated that the design of an A. F. C. system will be considerably simplified if that system has merely to vary, by relatively small amounts, the frequency of an oscillator which is not otherwise required to be variable.

According to this invention in its broadest aspect a superheterodyne receiver is characterised in that the received signal wave frequency is beaten down to a predetermined I. F. by local

oscillations which are obtained by mixing together oscillations from two local oscillators only one of which is continuously variable for manual tuning purposes.

According to an important subordinate feature of the invention a receiver in accordance with the main feature of this invention is fitted with an A. F. C. system which operates to control the frequency of that one of the two local oscillators which is not subjected to continuously variable manual tuning control.

A preferred form of superheterodyne receiver embodying both the above mentioned features of invention will first be described in general terms, practical frequency values being given in order to simplify the description. It is to be understood, however, that the invention is not limited to the adoption of the particular values of frequency to be given.

In the drawings, Fig. 1 represents a block diagram of so much of a superheterodyne receiver necessary for a proper understanding of the invention; Fig. 2 is a preferred and detailed circuit of a portion of the system shown in Fig. 1; Fig. 3 is a modified form of the system shown in Fig. 1, and Fig. 4 discloses the system of Fig. 3 with the application of fine and coarse A. F. C. controls.

Referring to Figure 1 signals picked up on a receiving aerial 1 are applied to the usual signal tuning means, for example the tuning circuit of a pre-selection radio frequency amplifier 2 having a tuning range of 150 to 1500 kc. The output from this pre-selection apparatus is passed to a first mixer stage 3 to which are also fed local oscillations obtained by mixing the oscillations from two local oscillators. One of these local oscillators 4 is variably tunable in a continuous manner for manual tuning purposes and has a frequency range of, say, 2.6 to 3.95 megacycles. This oscillator may, if desired, be remotely tuned, as indicated, by remote tuning apparatus 5. The other oscillator 6, hereinafter termed the "fixed" oscillator, is not manually tunable but its oscillatory frequency is arranged to be varied automatically over a required small range by an A. F. C. system. The (normal) frequency of the "fixed" oscillator 6 is in the present example, 2 megacycles. The term "fixed" is used for this oscillator because, although the frequency of the said oscillator is not actually fixed, it is not continuously variable manually and the said term, though not strictly accurate, is sufficient to distinguish the oscillator in question from the other oscillator 4. The outputs from

the two oscillators are fed to a local oscillation mixer stage 7 and the resultant output from this stage is passed through a band pass filter circuit 8 having a pass range of 600 to 1950 kc. to the first mixer stage 3. In place of a band pass filter a tunable circuit tunable over the range 600 to 1950 kc. can be provided in order that the oscillating input to the mixer 3 may be as free from harmonics as possible. The output from the first mixer stage 3 is fed to an I. F. amplifier 9 of normal design having a mid-band frequency of 450 kc. This I. F. amplifier is followed by a demodulating detector (not shown) and a low frequency amplifier (not shown) as in the usual way. Energy from a suitable stage in the I. F. amplifier is tapped off, separately amplified if desired by an amplifier 10 and passed to an A. F. C. discriminator network 11 of any suitable kind known per se. The discriminator output is fed to an A. F. C. control valve 12 which operates in any manner known per se to control the frequency of the "fixed" local oscillator 6 within the fairly narrow limits required for A. F. C. action.

In practice the two local oscillators 4, 6, and the two mixers 3, 7, of the above receiver may be embodied in a simple circuit employing only three valves. Such a circuit is shown in Figure 2. Referring to Figure 2 the first mixer (3 of Figure 1) is hexode 3A to whose first grid 3B the signal input from the unit 2 of Figure 1 (this is not shown in Figure 2) is applied. In the anode circuit of this hexode is a band pass fixed tuned twin circuit arrangement 3C of normal type which feeds into the I. F. amplifier 9 of Figure 1 (not shown in Figure 2). The variably tunable local oscillator is constituted by a back coupled triode 4A and its oscillatory output is taken to the first grid 7A of the hexode section of a triode hexode 76. The third grid 7B of this hexode section is directly connected to the control grid 6A of the triode section and in the circuit of the anode 6B of the triode section is included a tuned circuit 6C resonant at the predetermined "fixed" frequency chosen for the fixed local oscillator. The A. F. C. control valve 12 (not shown in Figure 2) operated through the discriminator network 11 (not shown in Figure 2) is connected in well known manner to act as an automatically controlled variable reactance connected between terminals T1, T2 of Figure 2 so as to form in effect part of the tuned circuit in the anode circuit of the triode section. The tuned circuit 6C is back coupled to the grid 6A so that the triode section of the valve 76 operates as the "fixed" local oscillator 6 of Figure 1 and since this grid 6A is connected to the third grid 7B of the hexode section and the first grid 7A of the hexode section receives oscillations from the valve 4A the said hexode section operates as the local oscillation mixer 7. Accordingly in Figure 2 the triode hexode is given the reference 76, since it performs the functions of the elements 7 and 6 of Figure 1. The anode circuit of the hexode section contains a tunable circuit 8 tunable over the range 600-1950 kc. (corresponding to the unit 8 of Figure 1) which is coupled to the third grid 3D of the hexode 3A. Thus the hexode 3A operates to produce the required I. F. since its first grid 3B receives incoming signals and its third grid 3D receives the resultant of mixing (in the hexode section) the two local oscillations.

The invention is not limited to receivers em-

bodying A. F. C. though its advantages are most manifest when it is so applied in the manner above described. Again the invention is not limited to receivers wherein the manually tunable oscillator is remotely controlled.

The broader feature of the invention, namely the use of two oscillators to beat together to produce the local oscillation frequency for heterodyning may with advantage be employed in connection with "band spread" tuning on short waves. In such an application the frequency of the "fixed" oscillator is arranged to be varied in discrete steps in such manner that each step taken in conjunction with the variable frequency range of the manually tunable oscillator, produces a range of resultant local oscillation beat frequencies which covers one of the broadcast or amateur short wave bands.

The invention is capable of application to superheterodyne receivers where—in order, for example, to obtain maximum sensitivity—two I. F. amplifiers of different frequencies are used. In such a case the "fixed" local oscillator may also be used to provide heterodyning oscillations to beat the first I. F. to the second I. F. Thus the embodiment of Figure 1 may be modified as shown in Figure 3 by following the 450 kc., I. F. amplifier 9 by another mixer 13 in turn followed by an I. F. amplifier 14 operating either at 2.45 megacycles or 1550 kc. Oscillations from the "fixed" 2 megacycle oscillator 6 are applied to the mixer 13 as well as mixed with the oscillations from the continuously tunable oscillator 4, to produce the second I. F. In such a case it is possible to provide two A. F. C. systems, if desired both operating via a common control valve on the same oscillator, namely the "fixed" oscillator. One of these A. F. C. systems operates to provide fine control and the other coarse control. This is shown in Figure 4. Here the fine control system includes a fine control A. F. C. discriminator network 910 fed from one I. F. amplifier (the amplifier 9) and the other A. F. C. system includes a coarse discriminator A. F. C. network 1410 fed from the other I. F. amplifier (the amplifier 14) both the networks 910 and 1410 operating to control a common A. F. C. valve 12'. Again the advantage is obtained that only one oscillator and that of substantially fixed frequency is controlled (the step by step variation in frequency is really only a variation to change the wave length range, the "fixed" oscillator being still of fixed frequency—apart from A. F. C. control—in any one wave band covered). The order of application of the fine and coarse A. F. C. systems and the choice of the intermediate frequencies are, as will be realised, arbitrary.

A double oscillator, single I. F. superheterodyne receiver such as that illustrated by Figure 1 is of advantage also for ultra-short wave reception. For example a band spread ultra-short wave receiver for receiving over the range 60-50 megacycles requires a local oscillation range of 60.45-50.45 megacycles if the I. F. is 450 kc. If the fixed oscillator frequency (from 6 of Figure 1) is 30 megacycles and the range of the oscillator 4 (Figure 1) is 20.45 to 30.45 megacycles, the summation of these two oscillator frequencies will give the required range of local oscillation frequencies for application to the mixer 3. To ensure frequency stability the fixed oscillator 6 may be crystal controlled (the A. F. C. system of Figure 1 would, of course, be omitted) and since the variable oscillator range is 20.45 to

30.45 megacycles it is more easily designed and more stable than would be a comparable oscillator with a tuning range of 50 to 60 megacycles.

The invention is also applicable to the reception of very long waves, e. g. waves up to 20,000 metres where again it offers advantages. Thus, in a system of the nature of that of Figure 1 by making the I. F. amplifier 9 of high selectivity and of a low frequency, say 12 kc. and by suitably choosing the frequency of the oscillator 6 and extending the coverage of the oscillator 4 so that the required range of low radio frequencies is produced for application to the mixer 3, long wave reception can be very efficiently achieved. The use in this way of two oscillators to produce the required local oscillations by beating with one another, avoids the need to construct a local oscillator with unduly large coils.

In the claims which follow the term "fixed" is employed with the rather special meaning already indicated herein to mean "not subject to continuously variable manual control for tuning purposes."

We claim:

1. In the method of superheterodyne reception, the steps which consist in selecting oscillations of the received signal wave, deriving oscillations from a local source of variable frequency, deriving other oscillations from a local source of fixed frequency, first mixing the oscillations from said local sources and then mixing the resultant oscillations with the selected received signal oscillations to produce oscillations of an intermediate predetermined frequency, mixing the latter oscillations with those of the fixed frequency source to produce oscillations of another intermediate frequency and utilizing a control voltage derived from both of said intermediate frequency oscillations to control and maintain constant the oscillations produced by the local source of fixed frequency.

2. In a superheterodyne receiver provided with a first mixer stage, an intermediate frequency amplifier coupled to said mixer stage, a manually tunable local oscillator, a fixed frequency local oscillator, a second mixer stage for mixing the oscillations from said oscillators, and a channel including a frequency selective network interconnected between the first and second mixer stages, characterized in that the fixed frequency oscillator and the second mixer are constituted by different sections of a double section discharge tube, each section having one or more grids and an output electrode, said fixed frequency oscillator section having a grid connected to a grid in the mixer section, said mixer section having another grid to which oscillations from the manually tunable oscillator are applied, the frequency selective network being connected to the output electrode of the mixer section and arranged to

impress the resultant oscillations upon the first mixer stage.

3. In a superheterodyne receiver, a signal channel comprising a first mixer stage, an intermediate frequency amplifier, a second mixer stage and a second intermediate frequency amplifier all connected in cascade, a manually tunable local oscillator, a fixed frequency local oscillator, a third mixer stage for mixing oscillations from said oscillators, a channel including a frequency selective network interconnected between the third and first mixer stages, and a channel for supplying oscillations from the fixed frequency oscillator to the second mixer stage.

15 4. A receiver as claimed in claim 3 wherein a fine acting discriminator is coupled to one of the intermediate frequency amplifiers, and a coarse acting discriminator is coupled to the other of said intermediate frequency amplifiers, and a frequency control tube is coupled to both of said discriminators and to the fixed frequency oscillator.

5. In a superheterodyne receiver, a signal channel comprising at least a first mixer stage, a first intermediate frequency amplifier, a second mixer stage and a second intermediate frequency amplifier all connected in cascade, a variably tuned local oscillator, a fixed frequency local oscillator, a third mixer stage for mixing the oscillations from both said oscillators, means for feeding the combined oscillations to the first mixer stage, a fine acting discriminator coupled to the first intermediate frequency amplifier, a coarse acting discriminator coupled to the second intermediate frequency amplifier, a frequency control tube coupled to both of said discriminators, and means for coupling the frequency control tube to the fixed oscillator.

40 6. In a superheterodyne receiver, a signal channel comprising at least a first mixer stage, a first intermediate frequency amplifier, a second mixer stage and a second intermediate frequency amplifier all connected in cascade, a variably tuned local oscillator, a fixed frequency local oscillator, a third mixer stage for mixing the oscillations from both said oscillators, said third mixer and the fixed oscillator being combined in one tube, means for feeding the combined oscillations to the first mixer stage, a fine acting discriminator coupled to the first intermediate frequency amplifier, a coarse acting discriminator coupled to the second intermediate frequency amplifier, a frequency control tube coupled to both of said discriminators, means for coupling the frequency control tube to the fixed oscillator, and means for feeding oscillations from the fixed oscillator to the second mixer stage.
